UNITED STATES PATENT OFFICE

ARTHUR VON FRANKENBERG, OF NEW YORK, N. Y., ASSIGNOR TO FRANKART, INC., OF NEW YORK, N. Y., A CORPORATION OF NEW YORK

DESIGN FOR A LAMP OR SIMILAR ARTICLE

Application filed February 4, 1930. Serial No. 34,403. Term of patent 7 years.

To all whom it may concern:

Be it known that ARTHUR VON FRANKENBERG, citizen of the United States, and resident of New York city, in the county of New York and State of New York, has invented a new, original, and ornamental Design for a Lamp or Similar Article, of which the following is a specification, reference being had to the accompanying drawing, forming part thereof, in which the figure is a perspective view of the design for a lamp embodying my new design.

Referring to the drawing and particularly to the features that are dominant, the lamp embodying the design comprises a base, a central lamp globe mounted thereon, and a pair of figures of nude girls kneeling on the base on opposite sides of and facing away from the globe.

I claim:

The ornamental design for a lamp or similar article, substantially as shown and described.

Dated, New York city, January 30, 1930.

ARTHUR VON FRANKENBERG.
